No. 12,068

DECEMBER 21, 1880

UNITED STATES PATENT OFFICE.

WINTHROP L. JACOBS, OF JERSEY CITY, NEW JERSEY, ASSIGNOR TO
HARTFORD CARPET COMPANY, OF HARTFORD, CONNECTICUT.

DESIGN FOR CARPET.

SPECIFICATION forming part of Design No. 12,068, dated December 21, 1880.

Application filed September 18, 1880. Term of patent 3½ years.

To all whom it may concern:

Be it known that I, WINTHROP L. JACOBS, of Jersey City, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure A is a circular figure with irregular edges and a flower-like center.

Figure B is a geometrical figure composed of parallelograms placed next to one another, and having between it and the figure I the ornamented band f.

The figure C is a figure with a flower-like center surrounded by various arbitrary figures.

The figure D is a circular figure resembling an open flower, from one side of which projects the ornamented band n.

The figures E, F, and G are composed, respectively, of smaller figures grouped round their respective centers, and a portion of each of those figures does not appear in the design.

The figure N has one side toothed, and on the other a projection which connects it with the figure J, which resembles an open daisy, and which is connected by a band-like figure with the figure K, composed of a rosette, branching leaves, and geometrical figures.

I is a circular figure joined to the figure A by the band r.

H is a geometrical figure connected with the figure C by the band s, and having in close proximity to it the figure e, consisting of a semicircle with leaves branching out from one portion thereof.

L is a rosette placed at the junction of the two bands j and m, which connect it with the figures C and D, respectively.

a is an irregular figure joined by the band h to the figure C.

b is a rosette joined to the figure A by the band p.

These various figures are connected one with the other by the bands already mentioned, and by the bands i connecting figures C and G, the band g extending from figure F, the band q running between figures A and B, and the

band t connecting figures A and N. The interstices between the figures are partly filled by geometrical patterns and by projecting leaves.

In one corner of the design is the group M, composed of the flower-like figure u, the overlapping circles O, and the figure d, resembling a crown with a band under it.

I claim—

1. The design for carpets, consisting of the figure A, substantially as shown.

2. The design for carpets, consisting of the figure B, substantially as shown.

3. The design for carpets, consisting of the figure C, substantially as shown.

4. The design for carpets, consisting of the figure D, substantially as shown.

5. The design for carpets, consisting of the figures A B q f s C h g, substantially as shown.

6. The design for carpets, consisting of the figures C D i j m n, substantially as shown.

7. The design for carpets, consisting of the figure G, substantially as shown.

8. The design for carpets, consisting of the figure F, substantially as shown.

9. The design for carpets, consisting of the figure E, substantially as shown.

10. The design for carpets, consisting of the group M, composed of the figures u o d, substantially as shown.

11. The design for carpets, consisting of the figure N, substantially as shown.

12. The design for carpets, consisting of the figure J, substantially as shown.

13. The design for carpets, consisting of the figure K, substantially as shown.

14. The design for carpets, consisting of the figures J and K, substantially as shown.

15. The design for carpets, consisting of the figure I, substantially as shown.

16. The design for carpets, consisting of the figure H, substantially as shown.

17. The design for carpets, consisting of the figures N J K, substantially as shown.

18. The design for carpets, consisting of the figures A B C D E F G H I J K L M N and a b d e f g h i j m n o p q r s t u, substantially as shown.

WINTHROP L. JACOBS.

Witnesses:

N. B. MARTIN,

WILLY G. E. SCHULTZ.
